UNITED STATES PATENT OFFICE.

ARTHUR W. WALKER, OF MALDEN, MASSACHUSETTS.

OPERATING DEVICE FOR DOORS.

Application filed April 1, 1927. Serial No. 180,158.

This invention relates to improvements in operating devices for doors. More especially it relates to a device for moving a door between open and closed positions within the container of which the door is a part, as for example an oven or pan container.

The invention provides simple and conveniently located means whereby a slight pull of an operating rod opens a door and a gentle push closes it. An important feature resides in the having of the door mounted so as to swing within the casing upon its opening movement, thereby to gain compactness and to eliminate the inconvenience incident to such a door opening outward. And, in cases where the container is to rest on or close to the floor, it is a feature that the operating handle may be at a convenient elevation and may be gripped by an operator without need for stooping so as to lift the door from the floor as would be the case with the usual constructions.

In the attainment of these ends the door is pivoted within the container and is connected with a lever operated by a rod extending forward of the door through the casing wall and carrying a handle. A spring connected to the lever affords balance for opening the door or for closing it, and also holds the door when in wide open state. The container bottom serves to limit the door's closing movement and a suitable stop limits its opening movement.

It is intended that the patent shall cover by suitable expression in the appended claims whatever features of patentable novelty exist in the invention disclosed.

In the accompanying drawings:

Figure 1 is an isometric of a device, without a cover, embodying the invention;

Figure 2 is an elevation in section on line 2-2 of Figure 1;

Figure 3 is an elevation in section on line 3-3 of Figure 1, but with a door open; and

Figure 4 is a plan with one door open and the other door closed.

Referring to the drawings a container 10 such as an oven has interiorly a medial plate 12 extending from front to back, between two doors 14 which are pivotally mounted at the front so as to close openings 16 in the front wall at each side of said plate.

Each door 14 consists of a closure element or door proper 14^a and a pair of arms 14^b which latter extend back into the container in planes perpendicular to the front to piv-

otal mountings 18, one of which is in a bracket 20 on an end wall of the container and the other of which has a bearing 22 on the medial plate 12. A vertical lever 24 having a function like a walking beam is mounted on plate 12 rearward of the door. Its lower arm 24^a has horizontal link connection, as at 26, with the door at a point above the axis 18 about which the door swings, so that a pull on this link can swing the door inward and upward over the pivot to open the door. The upper arm 24^b of the lever has horizontal link 28 which is a rod extending forward out through the front wall of the oven above the door. A knob or handle 30 may be provided on the end of this rod as a grip for manipulation of the door. A pull on rod 28 makes the link 26 pull the door 14 to open position, where the portion 32 of container wall serves as a stop. A tension spring 34, anchored at the rear, serves to hold the door in its wide open state, being connected to the arm 24^a of the lever 24. When the door is wide open its centre of gravity is rearward of, or nearly over, its axis, and the spring 34 is well able to hold it in such position; but when rod 28 is pushed rearward the door is pushed forward by lever 24 and link 26, and so the door swings to closed position under the control of the operator, the container bottom serving as a limitation on said closing movement. Suitable legs 36 may be provided if desired in a particular case.

Thus is provided simple and effectual means for operating a door which retreats into its container and is concealed from view when open. Small movement of the handle effects the needed relatively large rotating movement of the door, and consequently the handle need project but little when in its extended position. A compact and serviceable device results, requiring only a minimum of space for its operation. The arms 14^b are conveniently made of sheet metal continuous with that of the door, and in that case the sheet easily provides the point of attachment for the links at a proper location for operating the door by pull and push of link 26.

I claim as my invention:

1. Door mechanism, comprising the combination, with a container and its door, of arms extending inward from the door and a pivotal mounting for the arms at a little distance inward from the door, this said be-

ing the supports and axis on which the door swings; and linkage including a direction-changing lever, connected to one of said arms, and extending out of the container on 5 the same side thereof with the door, for actuation there by an operator to open and close the door.

2. Door mechanism, comprising the combination, with a container and its door, of 10 a pivotal mounting for the door, located in that direction which is inward of the container from the closed door, the door being adapted to swing open by moving inward in the container to a position beside the 15 pivot at a 90° turn from its closed position; there being an arm, rigid with the door, having a point whose travel when the door opens is an arc whose chord is approximately perpendicular to the closed position 20 of the door; and operating mechanism connected to the arm at said point and having a rod extending outward beyond the face side of the door for actuation by an operator.

25 3. Door mechanism, comprising the combination, with a door pivotally mounted on

a horizontal axis in the rear of the position which it occupies when closed, and adapted to open by swinging up and back to a position above said axis, of operating means 30 connected to the door to swing it between open and closed positions and having a part extending forward of said door for actuation there by an operator; and elastic balancing means connected and arranged to 35 sustain part of the weight of the door when it moves from open to closed position.

4. Door mechanism comprising, in combination, a door pivotally mounted on an axis in the rear of the position which it occupies 40 when closed and adapted to swing upward about said axis to open position; a lever mounted rearward of said axis having link connection with the door; a rod extending forward from said lever beside the path of 45 travel of the door to a point in front of the door and adapted to be actuated by an operator to move the door from open to closed position and from closed to open position.

Signed at Boston, Massachusetts, this thirtieth day of March, 1927.

ARTHUR W. WALKER.
